UNITED STATES PATENT OFFICE.

CHARLES A. CAMPBELL, OF NEW YORK, N. Y.

DESIGN FOR A GAS-LAMP.

No. 38,816.

Specification for Design.

Patented Sept. 17, 1907.

Application filed May 3, 1907. Serial No. 371,728. Term of patent 7 years.

To all whom it may concern:

Be it known that I, CHARLES A. CAMPBELL, a citizen of the United States, residing at Brooklyn, county of Kings, city and State of New York, have invented a new, original, and ornamental Design for a Gas-Lamp, of which the following is a specification, reference being had to the accompanying drawing, forming part thereof.

The figure is a side elevation of the lamp showing my new design.

I claim—

The ornamental design for a gas lamp substantially as shown.

CHARLES A. CAMPBELL.
